ABSTRACT OF THE DISCLOSURE

As chain link fencing is fabricated in a step-by-step manner, slats from a supply magazine are automatically inserted transversely of the advancing fencing to result in a fence structure suitable for dividing highways. Retractable guide heads for introducing the leading ends of the slats into the fencing are operated automatically with safeguards to halt the operation of the machine in the event of malfunctioning.

Background of the invention

Heavy woven wire fencing of the chain-link type is commonly fabricated by machines such as disclosed in the Bergandi Patent 2,625,961 and the Bergandi et al. Patent 3,144,887 issued Aug. 18, 1964, which two patents are hereby incorporated into the present disclosure by reference.

In the fabrication procedure taught by the two patents, two coils of wire are wound simultaneously on a revolving mandrel with the two coils interlinked as they are formed and then the two interlinked coils are advanced into interlinking engagement with previously formed coils of the completed fencing. The woven fencing is advanced intermittently with pauses for the addition of pairs of coils and during each pause means at a station along the path of advance of the finished fabric functions to twist wire ends together at the opposite longitudinal edges of the fencing.

As such woven wire fencing is viewed edgewise along a longitudinal side edge, the individual coils of the inter-linked series of coils are seen to form transverse passages that are open at both side edges of the fencing. It has been found that inserting slats into these transverse passages results in a fencing structure that is especially useful for dividing highways since the slats are effective to cut off the glare of the headlights of oncoming cars. Because of this special utility the demand for fencing incorporating slats has become widespread with rapidly mounting production figures. Unfortunately, however, the methods heretofore employed for incorporating the slats into the fencing are relatively expensive.

One procedure that has been followed is simply to stop the wire weaving machine periodically to permit several feet of the finished fencing to be stretched out on the floor so that workmen can insert the slats by hand while the machine is idle. Another procedure is to guide the finished chain link fabric over an extensive vertical path as the fencing leaves the coil-forming mandrel and to stop the machine periodically to permit manual insertion of the slats while the machine is idle.

Since a machine is inherently capable of fabricating wire fencing at a rapid rate, production is severely penalized by periodically stopping the machine for the insertion of slats manually. The pressing need is for a fabrication procedure that incorporates slats into the fencing without the penalty of decreasing the rate of fabrication of the fencing. The present invention meets this need and in

2

doing so greatly reduces the cost of producing slatted wire fencing.

Summary of the invention

From the initial wire weaving station at the rotating mandrel, the fencing moves past a second station where pairs of wire ends on the opposite longitudinal edges of the fencing are twisted together and then the finished fabric moves in a horizontal path past a slat station where pairs of slats are inserted during pauses in the intermittent advance of the fencing. At the slat station a magazine holds two stacks of slats side-by-side and periodically pusher elements on an endless sprocket chain push a pair of slats endwise from the magazine into the transverse passages of the woven wire fencing. In preparation for the slat-inserting operation, what may be termed a guide head temporarily advances from the leading end of the slat magazine to engage the woven wire fencing to serve as means to guide the pair of slats into a pair of coils or transverse passages of the fencing.

The cycle of operation of the fabricating machine is governed by a timer which periodically advances the woven fencing after a pause for the addition of a pair of coils of wire to the fabric at the weaving station. The timer provides a sufficient time interval for the wire weaving operation and the concurrent slat-inserting operation. In the event a safety switch fails to be tripped by the complete insertion of a pair of slats, the timer is automatically rendered ineffective and the machine stops.

By virtue of the described mode of operation, the slat-inserting mechanism operates concurrently with the weaving mechanism to provide the fencing with slats as fast as the fencing is woven. In comparison with the above-mentioned prior procedures for fabricating slatted fencing, the invention increases the rate of production as much as fourfold. In addition, only one man is required to run the machine and to keep the magazine supplied with slats, whereas three men are required to carry out the previous fabrication procedures.

The features and advantages of the invention may be understood from the following detailed description together with the accompanying drawings.

Brief description of the drawings

45 In the drawings, which are to be regarded as merely illustrative:

FIG. 1 is a fragmentary elevational view showing the slat magazine and the mechanism for periodically inserting pairs of slats into the finished fencing;

50 FIG. 2 is an elevational view of the leading end of the magazine as seen along the line 2—2 of FIG. 1;

FIG. 3 is a fragmentary sectional view showing how a pair of guide plates cooperate to stabilize the fencing in the region of the slat magazine;

55 FIG. 4 is a fragmentary plan view in the region of the magazine showing a pair of newly inserted slats in the wire fencing; and

FIG. 5 is a fragmentary elevational view showing how a dual stapler anchors the slats to the wire fencing at a fourth station beyond the slat magazine.

Description of the preferred embodiment

General arrangement

65 In a manner that is typical of machines of this particular type, a power driven rotary mandrel (not shown) is part of a cyclic mechanism that fabricates the woven wire fencing. Two spaced wires are wound simultaneously on the mandrel in such a manner that the result is two interlinked coils of wire and these two coils are linked with the finished fabric as they are formed. Thus each 70 cycle of operation produces two successive coils of the

woven wire fabric at a weaving station and at a second adjacent station pairs of cut wire ends at the opposite ends of the newly woven fabric are twisted together to unite the loose wire ends. The wire fencing is advanced intermittently along a given path with pauses in the advance for the weaving of new pairs of coils.

In the present embodiment of the invention, the woven wire fencing advances vertically upward from the weaving station and the adjacent wire twisting station and then as indicated in FIG. 1 changes direction over a guide means 10 to travel horizontally past a slat-insertion station represented by a slat magazine, generally designated 12 and then past a stapling station which is represented by a dual stapler, generally designated 14.

When the traveling woven wire fencing pauses intermittently, a guide head, generally designated 15, (FIGS. 1 and 4) is actuated by a solenoid 16 for extension from the slat magazine 12 into engagement with a pair of coils of the wire fencing to facilitate insertion of a pair of slats S into the wire fencing. The slat magazine 12 contains two stacks of the slats S side-by-side and a pair of pusher blocks 18 on a pair of endless sprocket chains 20 periodically engages the outer ends of the lower slats of the two stacks and pushes the two slats through the advanced guide head 15 into the woven fencing. After the pair of slats is fully inserted, the guide head 15 retracts and the cyclic mechanism advances the woven fencing another step. At each pause the dual stapler 14 at the stapler station applies staples to the newly added pair of slats to anchor the slats to the wire fencing.

FIG. 1 shows diagrammatically the timer 22 which is operated automatically at the end of each weaving cycle to initiate a new weaving cycle. The timer 22 is controlled by a microswitch 24 which is mechanically actuated by the cyclic mechanism. In this embodiment of the invention the microswitch 24 is operated by a cam or projection 25 on a shaft 26 at the wire-twisting station, which shaft makes a complete rotation in the course of each operating cycle.

The timer 22 provides a time interval that is adequate for the cycle of the weaving operation and is adequate to permit the insertion of a pair of slats from the slat magazine 12. At the proper time in the operating cycle, the solenoid 16 is energized to advance the guide head 15 and then the pair of sprocket chains 20 are actuated to cause a pair of the pusher blocks 18 to insert a new pair of slats into the woven wire fencing.

The extension of the guide head 15 operates a safety switch 28 shown in FIG. 1 and when a pair of pusher blocks 18 advances far enough for completely inserting a pair of slats into the woven fencing, a second pair of returning pusher blocks mechanically operates a microswitch 30 to cause the de-energization of the solenoid 16 and consequent spring actuated return of the guide head 15. The return of the guide head 15 releases the safety switch 28. In the event that the safety switch 28 is not released by return of the guide head 15, the safety switch prevents initiation of a new cycle by the timer and thus stops the machine when malfunctioning of the slat-inserting means occurs.

Only a single workman is required to supervise the operation of the machine and in addition to keep the slat magazine 12 replenished with new slats. If the machine stops automatically because of malfunctioning of the slat-inserting mechanism or because of malfunctioning of other parts of the machine that are operatively associated with corresponding safety switches, the workman takes the necessary steps to correct the situation with minimum loss of production time. Ordinarily the rate of production of the wire fencing with incorporated slats is substantially the rate of production of conventional wire fencing without slats.

Structural details

The slat magazine 12 shown in FIGS. 1, 2 and 4 includes spaced upright members 32 which confine two sup-

ply stacks of the slats S side-by-side. The floor of the magazine has longitudinal openings or slots (not shown) through the pusher blocks 18 travel to push on the rear or outer ends of the slats of the two stacks.

For actuating the two sprocket chains 20, a motor 24 actuates a drive shaft 35 by reduction gearing in a gear box 36 and a drive sprocket 38 is operatively connected to the drive shaft by a friction clutch 40 which is adjustable by means of a nut 42. If the load on the drive sprocket 38 rises unduly, the friction clutch slips. Thus if the advancing slats meet an obstacle, the two sprocket chains 20 stop without incurring damage to the machine parts.

As shown in FIG. 1 the drive sprocket 38 is connected by a sprocket chain 44 to a sprocket 45 on a shaft 46, the sprocket being directly connected to a pair of drive sprockets 48 on the chain shaft that actuate the two sprocket chains 20 respectively of the magazine mechanism. The shaft 46 is journaled in a bracket 50 on the front end of the magazine which bracket is forwardly adjustable. In the construction shown, the bracket 50 has two arms 52 on opposite sides of the magazine structure which are formed with slots 54 to receive corresponding studs 55 that carry corresponding nuts 56. At the rear or outer end of the magazine structure a second similar adjustable bracket 50 journals a shaft 60 that carries a pair of idler sprockets 62 for the two sprocket chains 20 respectively. It is apparent that the two brackets 50 and 58 may be adjusted to vary the position of the two sprocket chains 20 relative to the woven fencing thereby to adjust the extent to which the pusher blocks 18 insert the slats into the woven fencing.

It is to be noted that there are two pairs of the pusher blocks 18 with the two pairs at equal spacing on the two sprocket chains 20. When one pair of pusher blocks is moving forward to push a pair of slats into the woven fabric, the other pair of pusher blocks is returning on the lower flights of the sprocket chains towards the switch 30, the switch 30 being located to allow for coasting of the pusher blocks to a stop.

As may be seen in FIG. 4, the guide head 15 is tapered in plan to form a tapered nose 64 to facilitate insertion of the guide head into the entrance to a pair of coils or transverse passages of the woven wire fencing. As shown in plan in FIG. 4 the two opposite sides of such an entrance are defined by two spaced twisted wire joints 65 where converging wire ends come together. As shown in FIG. 2 the guide head 15 has two pairs of longitudinal flanges 66 for sliding support of a pair of slats S, the flanges being spaced to clear the path of the pusher blocks 18.

A fixed vertical plate 68 is spaced forward from the magazine 12 and is supported from the magazine by a pair of parallel horizontal arms 70 and a lower guide rod 72. The guide head 15 is mounted on the underside of a carriage 74 that is slidably confined by the two arms 70 and is slidably mounted on the guide rod 72. As shown in FIG. 1, the previously mentioned safety switch 28 is mounted on the rear face of the vertical plate 68 and is actuated by an operating finger 75 that is fixedly mounted on the upper side of the carriage 74.

The previously mentioned solenoid 16 is mounted on the forward end of the magazine 12 and the armature 76 of the solenoid is connected by a link 78 with one arm of a lever 82 that is pivotally mounted on a fixed bracket 84. The second arm of the lever 82 is connected by a link 85 to the forward end of the carriage 74 so that retraction of the armature 76 by energization of the solenoid 16 causes the guide head 15 to advance into engagement with an entrance to a pair of coils or transverse passages of the woven wire fencing with consequent operation of the safety switch 28. A suitable coil spring 86 connected to the lever 82 continuously urges retraction of the guide head 15.

Mounted on pivot pins 88 (FIG. 4) on opposite sides of the guide head 15 is a pair of spreader fingers 90 the function of which is to engage opposite sides of the en-

trance to a pair of coils or transverse passages of the woven fencing to make sure that the entrance is spread sufficiently to receive the pair of slats. Normally the spreader fingers are held in the retracted positions shown in FIG. 4 by means of suitable springs (not shown) with the two spreader fingers in the path of advance of the pair of slats. With the guide head advanced into engagement with the wire fencing, the subsequent advance of the two slats causes the slats to brush the fingers 90 to one side thus causing the fingers to swing to the positions shown at 90a in FIG. 4 for spreading action against the wire fencing.

To make sure that the wire fencing is in the same plane with the guide head, the woven wire fencing may be suitably confined in the region of the slat-insertion station. For this purpose an upper guide plate 92 shown in FIGS. 3 and 4 cooperates with a lower guide plate 84 to confine the woven wire fabric from opposite sides.

Since it is possible that a pair of slats may be advanced too far and thus protrude from the far edge of the woven wire fabric, a suitable stop plate 95 may be provided adjacent the far side of the woven fencing as shown in FIG. 4. A portion 95a of the stop plate that is positioned directly opposite the magazine 12 converges on the path of travel of the woven wire fencing and leads to a second portion 95b that is immediately adjacent the path. Thus if an inserted slat protrudes beyond the far side of the woven fabric at the slat-insertion station, the portion 95a of the stop plate 95 will function as a cam to retract the slat to its proper position in response to advance of the slat to the stapling station.

At the stapling station, the dual stapler 14 comprises a pair of stapler units 96 mounted on a common support 98. In FIG. 5 the dual stapler is poised above the woven wire fabric and an anvil plate 100 is positioned below the woven wire fencing to limit the displacement of the fencing by the operation of the dual stapler. Each of the two stapler units 96 drives a staple 102 into the corresponding slat with the staple positioned to straddle a diagonal wire 104 of the woven fencing. The dual stapler operates automatically during each pause in advance of the woven fencing.

Our description in specific detail of the presently preferred embodiment of the invention will suggest various changes, substitutions and other departures from my disclosure within the spirit and scope of the appended claims.

I claim:

1. In an apparatus for weaving wire fencing of inter-linked wire coils wherein the apparatus advances the finished woven fabric longitudinally intermittently along the given path and cyclic mechanism weaves a new coil into the fabric at each pause in the advance, the improvement for inserting slats into the coils of the finished fabric, comprising:

magazine means at an insertion station alongside said path adjacent a side edge of the finished fabric; and means responsive to said cyclic mechanism and operative through a cycle at pauses in the advance of the finished fabric to insert slats from said magazine means endwise into the coils of the fabric, whereby the wire fabric is equipped with slats concurrently with the weaving of the fabric.

2. An improvement as set forth in claim 1 which includes guide means at said insertion station to facilitate the insertion of the slats into the coils of the finished fabric.

3. An improvement as set forth in claim 2 in which said guide means includes means to confine the woven fabric against displacement out of its plane at the insertion station.

4. An improvement as set forth in claim 2 in which said guide means includes cyclic means to engage the entrance of the coils of the woven fabric to facilitate entry of the slats into the coils.

5. An improvement as set forth in claim 1 which includes means responsive to operation of said slat-inserting means to prevent continued operation of said cyclic mechanism when the slat-inserting means fails to complete its cycle.

6. An improvement as set forth in claim 1 which includes means operative at pauses in the advance of the woven fabric to anchor the inserted slats to the woven fabric.

10 7. An improvement as set forth in claim 6 in which said anchored means includes stapling means and cooperative anvil means.

15 8. An improvement as set forth in claim 1 which includes power means to operate said slat-inserting means and in which the power means is operatively connected to the slat-inserting means by friction clutch means that slips in the event that obstacles prevent complete insertion of the slats.

20 9. In an apparatus for weaving wire fencing of inter-linked wire coils wherein the apparatus advances the woven fencing longitudinally intermittently along a given path and cyclic mechanism weaves an addition to the fencing at each pause in the advance, the improvement for inserting slats into the coils of the fencing, comprising: magazine means to hold a supply of slats at an insertion station alongside said path adjacent a side edge of the fencing;

25 a guide head extendible from said magazine means into engagement with the entrances of the coils of the fencing to facilitate insertion of slats into the coils; means operative through cycles at pauses in the advance of the fencing to insert slats from said magazine means endwise through said guide head into the fencing; means to extend said guide head during pauses in the advance of the finished fencing; means to operate said slat inserting means when the guide head is advanced; and means to retract the guide head after the slats are completely inserted into the fencing.

30 10. An improvement as set forth in claim 9 which includes guide fingers on said guide head to engage the entrances of the coils of the woven fencing to facilitate insertion of the slats into the coils.

35 11. An improvement as set forth in claim 10 in which the leading ends of the slats operate said guide fingers by cam action for spreading effect on the entrances to the coils of the woven fencing.

40 12. An improvement as set forth in claim 9 which includes means responsive to extension of said guide head to prevent continued operation of said cyclic mechanism in the event that the guide head fails to retract.

45 13. An improvement as set forth in claim 9 which includes means to sense completion of the insertion of the slats into the coils of the woven fabric; and in which said means to retract the guide head is responsive to said sensing means.

50 14. In an apparatus for weaving wire fencing of inter-linked wire coils wherein the apparatus advances the finished fencing longitudinally intermittently along a path and cyclic mechanism weaves a pair of new coils into the fencing at each pause in the advance of the fabric, the improvement for inserting slats into the coils of the finished fabric, comprising:

55 magazine means at an insertion station alongside said path adjacent a side edge of the finished fabric to hold a supply of pairs of slats; means responsive to said cyclic mechanism and operative through a cycle at each pause in the advance of the woven fabric to insert a pair of slats from said magazine endwise into a pair of coils of the fencing, whereby the fencing is equipped with pairs of slats as fast as pairs of coils of wire are added to the fabric.

60 15. An improvement as set forth in claim 14 which includes guide means at said insertion station to facilitate

the insertion of a pair of the slats into a pair of the coils of the woven fabric.

16. An improvement as set forth in claim 14 which includes a guide head extensible from said magazine into engagement with the entrances of a pair of coils of the fabric to facilitate insertion of a pair of slats into the pair of coils; and

which includes means responsive to said cyclic mechanism to extend said guide head at pauses in the advance of the woven fabric prior to the operation of the slat-inserting means.

17. An improvement as set forth in claim 16 which includes means to sense completion of the insertion of a pair of slats into the woven fabric; and

which includes means to retract the guide head in response to said sensing means.

18. An improvement as set forth in claim 17 which includes means responsive to advance of the guide head to prevent continuation of the operation of the cyclic mechanism in the event of incomplete insertion of the slats into the woven fabric.

19. An improvement as set forth in claim 16 which includes sprocket chain means to push the pairs of slats from the magazine means into the coils of the fencing and which includes switch means responsive to said sprocket chain means to cause retraction of said guide head when a pair of slats is completely inserted into the woven fabric.
